CLAIM

I claim the ornamental design for the pill case, as shown and described.

DESCRIPTION

FIG. 1 is a top front right perspective view of the pill case according to a first embodiment of the new design;

FIG. 2 is a bottom front left perspective view of the pill case of FIG. 1;

FIG. 3 is a top plan view of the pill case of FIG. 1;

FIG. 4 is a right side elevation view of the pill case of FIG. 1, the left side being substantially a mirror image thereof;

FIG. 5 is a front elevation view of the pill case of FIG. 1;

FIG. 6 is a bottom plan view of the pill case of FIG. 1;

FIG. 7 is a rear elevation view of the pill case of FIG. 1;

FIG. 8 is a top front right perspective view of the pill case according to another embodiment of the new design;

FIG. 9 is a top plan view of the pill case of FIG. 8;

FIG. 10 is a left side elevation view of the pill case of FIG. 8;

FIG. 11 is a right side elevation view of the pill case of FIG. 8;

FIG. 12 is a front elevation view of the pill case of FIG. 8;

FIG. 13 is a bottom plan view of the pill case of FIG. 8; and,

FIG. 14 is a rear elevation view of the pill case of FIG. 8.
